(57) **CLAIM**

The ornamental design of a round lamp, as shown and described.

DESCRIPTION

FIG. 1 is a perspective view of a round lamp;

FIG. 2 is the perspective view of the round lamp with a mounting bracket;

FIG. 3 is a front view of the round lamp with the mounting bracket;

FIG. 4 is a rear view of the round lamp with the mounting bracket;

FIG. 5 is a side view of the round lamp;

FIG. 6 is the side view of the round lamp with the mounting bracket.

FIG. 7 is an opposite side view of the round lamp with the mounting bracket;

FIG. 8 is a top view of the round lamp with the mounting bracket;

FIG. 9 is a bottom view of the round lamp; and,

FIG. 10 is the bottom view of the round lamp with the mounting bracket.

The broken line showing of the mounting bracket is for the purpose of illustrating environmental structure for the round lamp and forms no part of the claimed design.
